UNITED STATES PATENT OFFICE.

TATSUJIRO IMAIZUMI, OF SEATTLE, WASHINGTON.

LIFE-RAFT.

1,326,866.

Specification of Letters Patent.

Patented Dec. 30, 1919.

Application filed November 6, 1918. Serial No. 261,357.

To all whom it may concern:

Be it known that I, TATSUJIRO IMAIZUMI, a subject of the Emperor of Japan, and resident of the city of Seattle, county of King, 5 and State of Washington, have invented certain new and useful Improvements in Life-Rafts, of which the following is a specification.

My invention relates to life rafts. The 10 object of my invention is to provide an improved type of construction for life rafts, one which shall have great carrying capacity for its weight, which may be partially collapsed so as to take up but little 15 room, and which, when in use, may provide protection against the occupants being washed away, and also to a considerable extent, protection from waves entering thereon in such manner as to wet the occupants. 20

My invention consists of the novel features which will be hereinafter described and then particularly pointed out in the claim.

25 The accompanying drawings show the preferred manner of constructing a raft in accordance with my invention.

Figure 1 is a partial plan view of the frame within which the flotation members 30 are secured.

Fig. 2 is a partial plan or face view of the upper main frame, showing the reinforcing net and the canvas employed therewith.

Fig. 3 shows in perspective, the complete 35 raft set up, or as it would be when in use.

Fig. 4 shows in perspective, the raft in its collapsed form, or as it would be while stored aboard ship.

Fig. 5 shows in perspective, a detail only 40 of the side members which may be folded down against the frame when not in use and raised to a vertical position when in use.

The weight carrying members of this 45 raft consist of hollow cylinders or equivalent members, C, which are held in place within a frame, of which A represents one of the top bars and B one of the bottom bars. Such a frame is shown in partial plan in Fig. 1, together with the flotation members 50 therein. These frames are secured together by vertical bolts or other suitable manner.

The form of raft shown is one having two 55 long sides and at each end of the rectangle thus formed, two shorter sides forming a triangle. The outline of the raft is thus a

six-sided polygon, elongated in one direction. The bars F, which form a part of the upper main frame, have secured thereto a reinforcing netting, preferably of woven 60 wires, or small metal rods. This netting E is immediately beneath the bars F and beneath this netting is a layer of canvas.

In securing the canvas and the netting to the bars F, I prefer to employ bolts G, 65 having washers of some compressible material, as rubber, and also to employ cement of some sort to make a tight joint, so that there will be no leakage because of using the bolts. 70

To each side of the main body of the raft is secured a side piece consisting of a frame having thereon wire netting Q and outside of this canvas D. This canvas is preferably 75 also secured to the canvas which is beneath the floor so as to make a tight joint and thus prevent the ingress of water.

The type of construction of the sides is illustrated in the perspective shown in Fig. 5. This side is typical of the others. The 80 vertical bars S are secured by hinges P to the outer side bar F of the frame which supports the floor. They may thus fold down when the raft is not in use. When turned upward they are secured, as by hinge and 85 pin connection such as shown at R, to the top marginal rails, of a top frame J which serves as a means for retaining the sides in position, adds rigidity to the structure and also serves in the mounting of masts as is 90 presently described.

With the sides thus raised and secured in place, the occupants of the raft are protected from the direct actions of the waves and would be saved from getting wet many 95 times, when otherwise the raft would be flooded.

By using the wire netting Q inside of the canvas the strength of the canvas is reinforced so that the waves will not tear the 100 canvas loose unless the waves are very strong.

I provide two transversely extending bars H which are secured to the ends of the side bars J and which serve to reinforce the upper 105 edges of the sides, and also to form a support for the masts L. To the frame of the floor is secured two blocks N, which are provided with a hole, M, into which is stepped the lower ends of the mast L. These masts 110 are also engaged in the notches of the bar H, or in any other suitable manner secured rela-

tive thereto and are connected at their upper ends by a stay K. The upper ends of the mast are also stayed by ropes O which extend downwardly and are secured to the raft itself, as by means of the rings I.

5 In this manner the masts are held supported and may be collapsed with the sides when the raft is not in use. These masts may serve for the installation of sails, or 10 for supporting signals.

When not in use the raft would be collapsed and would appear as shown in Fig. 4. When launched the sides would be raised and secured in place and the mast L might 15 be put up at any time desired. Such a raft would take up but little storage space and would carry a very large load. Having the upwardly extending sides, which, being covered with canvas would keep out the 20 water, the occupants of the raft would be kept dry when otherwise they would become drenched. The raft is, therefore, much

more comfortable than a plain, open raft, and in addition is much safer, as people might often be washed off from an ordinary 25 open raft when there would be no danger of this happening with a raft as I have herein shown.

What I claim as my invention is:

A life raft comprising a base frame in- 30 closing flotation members, an upper frame conforming in shape to the base frame but separate therefrom, sides permanently hinged by their lower edges to the edges of the base frame adapted to fold against the 35 base or to be raised to form an inclosure, the upper edges of said side having locking members coöperating with complementary members on the upper frame whereby the latter may be removably locked on the sides 40 when the latter are raised.

Signed at Seattle, Washington, this 30th day of October, 1918.

TATSUJIRO IMAIZUMI.
